TOILET TISSUE HOLDER

Paul F. Simpson, Washington, Conn., assignor to The Autoyre Company, Inc., Oakville, Conn., a corporation of Connecticut

Application February 24, 1949, Serial No. 1,069

Term of patent 14 years

(Cl. D4—3)

To all whom it may concern:

Be it known that I, Paul F. Simpson, a citizen of the United States, residing in Washington, State of Connecticut, have invented a new, original, and ornamental Design for Toilet Tissue Holder, of which the following is a specification, reference being had to the accompanying drawing, forming a part thereof.

Fig. 1 is a perspective view of a toilet tissue holder showing my new design, the wall bracket and support for a tissue roll having been shown in dotted lines;

Fig. 2 is a plan view of the toilet tissue holder of Fig. 1, and

Fig. 3 is a front view of the design of Fig. 1, the support of Fig. 1 having been removed.

The dominant features of my new design have been illustrated in the drawing in full lines.

I claim:

The ornamental design for a toilet tissue holder, substantially as shown and described.

PAUL F. SIMPSON.
